Primary Examiner — Cynthia R Underwood(74) *Attorney, Agent, or Firm* — Paratus Law Group, PLLC(57) **CLAIM**

The ornamental design for a cover for electronic device, as shown and described.

DESCRIPTION

FIG. 1 is a front, top, and right side perspective view of a cover for electronic device, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, bottom, and left side perspective view thereof; and,

FIG. 9 is a rear, bottom, and right side perspective view thereof.

The broken lines in FIG. 3 illustrate the portions of the design that form no part of the claimed design.

1 Claim, 7 Drawing Sheets(56)
